SIGNAL DELAY CIRCUIT

Richard K. Gerlach, Gardena, and Royal E. Howes, Inglewood, Calif., assignors to The National Cash Register Company, Dayton, Ohio, a corporation of Maryland

Filed July 22, 1959, Ser. No. 828,910
13 Claims. (Cl. 346—174)

The present invention relates to signal translator circuits and more particularly to a signal translator circuit for providing a signal delay having a time period which is readily adjustable.

Generally, the present invention is directed to methods and apparatus for delaying signals by storing a predetermined magnitude of magnetic flux in a core of magnetic material wherein the flux magnitude is a function of the desired time period of delay. The signals to be delayed reverse the direction of flow of substantially only the stored magnetic flux in the core and the signals are delayed for a time period dependent upon the time period required for the reversal of stored magnetic flux.

In the preferred arrangement of the invention, the time period of delay of the signals is controlled electronically. Certain types of cores which are formed from magnetic material have been found to have desirable characteristics which are inherently well suited for electronically controlling the time period of the delay of signals.

The cores of the preferred type are formed of magnetic material having a high residual magnetism and a hysteresis characteristic curve which is substantially rectangular. The preferred cores have a plurality of apertures wherein the storage and adjustment of predetermined magnitudes of magnetic flux in paths about an aperture is readily accomplished electronically. By the inclusion of these cores having a plurality of apertures or multi-apertured cores in the translator circuits, the time period of delay can be varied over the range of magnetic flux storage capacity of the individual core. Further, in a preferred circuit arrangement, the time period of delay of signals has been made to correspond directly to the volt-microsecond integral of a setting signal.

Another advantage of the cores having a plurality of apertures included in the preferred embodiment of the translator circuit is that a single setting signal can provide for the storage and use of a magnitude of magnetic flux indefinitely and the magnitude of said magnetic flux stored can be accurately adjusted by controlling the time interval of the setting signal. It is an object therefore, of the present invention, to provide a signal translator circuit of the type described above for delaying signals.

Another object of the present invention is the provision of a delay for signals and controlling the period of delay electronically.

Another object of the invention is the provision of delay of a signal wherein the period of delay is adjusted by controlling the magnitude of magnetic flux stored in a core of magnetic material.

A further object is to provide a method of delaying a signal for a time period required to reverse a predetermined magnitude of magnetic flux stored in a core of magnetic material.

A still further object of the invention is the provision of a method for delaying changes in logical level of a signal wherein the duration of delay is controlled by the duration of another signal.

Another object of the invention is to provide apparatus for the delay of a signal wherein the period of delay corresponds directly to the time interval of another signal. Further objects and features of the invention will be

2

readily apparent to those skilled in the art from the specification and appended drawings illustrated for certain preferred embodiments in which:

FIG. 1 is a circuit diagram of the preferred embodiment of the invention;

FIG. 2 is a graph showing typical waveforms of certain signals utilized in the operation of the preferred circuit embodiment of FIG. 1;

FIG. 3 is a circuit diagram of a portion of the preferred embodiment shown in FIG. 1 to illustrate the circuit in a state providing a typical time period of delay;

FIGS. 4a and 4b are typical hysteresis characteristic curves which will result from interrogation of the large and small apertures respectively of a multi-apertured core as illustrated by the preferred embodiment in FIG. 1;

FIG. 5 is a circuit diagram of an alternate embodiment of the invention;

FIG. 6 illustrates waveforms of typical signals employed during the operation of the alternate embodiment shown in FIG. 5;

FIG. 7 is a graph of a typical hysteresis characteristic curve of a translator core in the alternate embodiment of FIG. 5.

Referring now to the drawings wherein like reference characters designate like or corresponding parts throughout the several views, there is shown in FIG. 1, which illustrates a preferred embodiment, a signal translator circuit arrangement for delaying signals. The translator circuit includes a translator core 12 having a plurality of apertures for storing predetermined magnitudes of magnetic flux to provide corresponding signal delays. The circuits for storing the magnetic flux include a clearing circuit 14 for applying a magnetizing force to the translator core to saturate the core with magnetic flux in one direction; and a setting signal circuit 16 for coupling setting signals to the translator core for partly reversing the direction of this magnetic flux and thereby storing the desired magnitude of magnetic flux in the core.

The signal to be delayed is coupled to the input of a signal delay circuit 18 which latter is inductively coupled to the core. The signals in the output of this circuit are delayed for a time period determined by the setting signals. A resetting circuit 20 resets the translator core 12 and supplies a signal to the output of the signal delay circuit 18 to effect delay of the trailing edges of the signals being delayed.

The translator core 12 employed in the circuit of the present invention stores magnitudes of magnetic flux wherein the magnitudes of magnetic flux are a function of the desired durations of signal delay.

The translator core 12 provides a convenient and reliable means for storing magnitudes of magnetic flux in a core within the individual magnetic flux capacity of cores. The magnetic flux stored in an individual core can be varied from zero to an amount saturating an annular minor flux path 24, indicated by dotted lines in FIGS. 1 and 3, surrounding a minor aperture 30. The maximum storage capacity of the signal translator core 12 is determined by the maximum residual magnetic flux capacity around the minor aperture 30. In turn, the maximum time period of delay is limited to the time interval required for the reversal of the magnetic flux stored in the core in flux paths around the minor aperture 30, wherein the time interval does not exceed the time interval between variations in the levels of the signals, in order to prevent losses in portions of the signals.

A more detailed explanation will next be presented of how a multi-apertured core, such as the core element 12 having at least two apertures including a minor aperture 30 and a major aperture 32, can be used to store mag-

netic flux which is available to interrogating windings threaded through the minor aperture.

The initial step in storing a magnetic flux, which will be available for use, is to apply a magnetizing force to the translator core to saturate the core with magnetic flux in a first direction.

In the preferred arrangement shown in FIG. 1, the translator core 12 can be so initially saturated, as indicated by the arrows, by applying a magnetizing force to the core produced by a current through a winding threaded through a major aperture 32 and wound about an outer core portion 36. Preferably, the cross sectional area of the core portion 36 is substantially equal to the sum of the cross sectional areas of core portions 38 and 40, and the cross sectional areas of core portions 38 and 40 are also substantially equal. The stated core parameters provide for greater efficiency in the use of core material whereby the maximum storage of magnetic flux around the minor aperture is determined by the core dimensions.

A reversal of the initial magnetic flux in the path about the major aperture 32, produced by a demagnetizing force applied to the core, stores in the path about the minor aperture 30 of the core a predetermined magnitude of flux which is available for use. In FIG. 3, arrows 42 and 44 indicate the direction of a typical resultant magnetic flux flow immediately surrounding the aperture 32 as the result of providing a magnetic flux storage around aperture 30.

Since the demagnetizing force producing the magnetic flux reversal tends to reverse the flow of flux in shorter magnetic paths before reversing the flux in longer paths, the reversal of the initial magnetic flux commences immediately adjacent the annular periphery of the major aperture 32, and the reversal of magnetic flux extends radially from the major aperture with an increasing demagnetizing force produced by the setting signal. Having once stored magnetic flux in the flux paths around the minor aperture, this stored flux is reversed in direction in the process of translating signals by a magnetizing force applied to an outer core portion 38 and produced by a winding threaded through the minor aperture and wound around the core portion 38. The magnetic flux flow in the minor path, which is available for reversal in response to interrogation by windings around core portion 38, is the stored magnetic flux. The time interval required for reversal of this stored magnetic flux by the signal to be delayed is the time period of delay.

The previous discussion of the operation of the translator circuit is consistent with the theory that the energy required to reverse the flow of magnetic flux in an annular flux path about the aperture of a core increases with the radial distance of the flux path from the inner periphery of the core about the aperture. Also, magnetic flux flow in opposite directions can saturate a core in different areas simultaneously while the whole core will be in a state of partial saturation. In view of the foregoing, it is apparent that after initial saturation of the core 12 by a magnetic flux flow in a clockwise direction, by a clearing signal coupled to the clearing winding 34, a magnetic flux can be stored around the minor aperture 30 of the core by the application of a control or setting signal having a constant voltage and a time interval which is controlled, to adjust the magnitude of the stored magnetic flux. The resulting state of the translator core, wherein magnetic flux flow is in opposite directions simultaneously about the major aperture, is a state of partial saturation.

FIG. 3 illustrates the translator core 12 after a setting signal has been applied to the translator circuit to store a magnitude of magnetic flux. The magnetic flux in flux paths around the major aperture 32, indicated by arrows 42 and 44, have been reversed to thereby form the annular minor flux paths around the minor aperture 30. The magnetic flux in annular flux paths around the minor aperture 30, as indicated by arrows 38 and 44, is the magnetic flux stored in the translator core.

The magnetic flux flow in FIG. 3 is typical; however, it should be realized that the flux flow produced by a single setting signal represents a single predetermined magnitude of magnetic flux only which is stored in the translator core 12, and the magnetic flux stored varies with different desired delay periods. For example, a relatively short setting signal applying a small demagnetizing force to the core for relatively short time periods of delay will reverse, and thereby store, only a small quantity of magnetic flux in the core. Under these conditions, only a small amount of magnetic flux will be reversed around the major aperture 32 and only a small amount of flux will be flowing in annular minor flux paths about the minor aperture 30. As stated previously, the magnetic flux flow in the annular minor flux paths is stored magnetic flux wherein the flux magnitude in the minor paths is a function of the time period of delay. Further, the time interval of reversal of the stored magnetic flux and therefore the time period of delay is a function of: the flux magnitude, the amplitude of the signal coupled to the core and the number of turns of windings threaded through aperture 30 and wound about outer core portion 38.

In FIG. 4a, the magnetic flux and magnetizing force have been plotted to show the transition in steps from the residual state of magnetism 1 corresponding to saturation in a first direction following a clearing signal 54 to successive residual states of magnetism corresponding to saturation in the opposite direction by sequential application of signals to a setting winding 46. The states of partial saturation of the core, after each setting signal, have been indicated by the typical residual magnetic states of magnetism 2 to 6. The sequential application of setting signals will move the residual state of magnetism of the translator core, in steps, from residual states 1 to 7 in a path such as indicated by the dotted line connecting the residual magnetic states 1 to 7. The magnitudes of stored magnetic flux in the flux paths 24 around the minor aperture 30 and the related hysteresis characteristic curves which correspond to residual states of magnetism 1 to 7 of the translator core 12, are indicated in FIG. 4b by curves 1a to 7a. It can be seen by an examination of these curves that the residual state 4 of the translator core provides a maximum magnetic flux storage around the minor aperture 30 wherein hysteresis curve 4a corresponds to the residual state 4 of the translator core 12.

In order to produce a stored magnetic flux of predetermined magnitude in the translator core 12, the demagnetization force applied to the core is produced by a volt-microsecond signal having a predetermined constant voltage and a predetermined time period. The signal is coupled to the setting winding 46 which is threaded through the major aperture 32 and wound around the outer core portion 36. It should be noted that the setting winding may be wound about an inner core portion 40. The polarity of the setting signal and the direction of the winding is such that a translator core initially saturated by a clearing pulse is demagnetized a predetermined amount by reversing the flow of magnetic flux in the core; and, more particularly, by reversing the direction of magnetic flux in the core adjacent to the aperture 32, wherein the radial distance of reversed magnetic flux from the aperture 32 increases as the setting signal time interval increases.

The signals to be delayed are coupled to the translator core by a signal delay winding 48 which is threaded through the minor aperture 30 and wound around the outer core portion 38. The signals reverse the direction of the stored magnetic flux around the minor aperture 30 and are delayed during the period of reversal.

It is readily apparent from the foregoing discussion that by a proper choice of corresponding supply voltages and number of turns of the windings around the core that the time period of delay can be made to correspond directly to the time interval of a setting signal. In order

to insure a constant supply voltage for the signal windings 48 and the setting winding 46, the supply circuits have been arranged to limit the supply voltage whereby the translator core 12 is set into a condition of partial saturation by the amount of flux determined by the time interval of the setting signal coupled to the input of the setting circuit.

In the signal delay circuit 18, the initial variations of the signal wave forms or the leading edges coupled to the input are delayed in the output by adjusting the magnetic flux stored in the minor flux paths about aperture 30. During the period of delay, the signal energy is dissipated in reversing the stored magnetic flux. Since the signal energy is not returned to the delay circuit output, an additional provision must be made to the circuit arrangement for delaying the return variations or trailing edges of the signal waveforms.

The resetting circuit 20 has been provided for resetting the stored magnetic flux flow in the translator core and also for aiding in delaying the return variations of the signal waveforms in the signal delay output circuit. The resetting circuit includes a winding 50 threaded about core portion 38 of the minor aperture 30. The winding 50 is coupled to a supply voltage source through a current limiting resistor 52 and a clamping voltage source through a diode 84, whereby the current amplitude is limited to produce a magnetizing force which is sufficient to reset the stored magnetic flux only about aperture 30. The level of the magnetizing force produced by the resetting circuit is too low to disturb the flux in the flux path around the major aperture 32. Thus, the reset circuit 20 resets the flux about minor aperture 30 to prepare for delay of subsequent signal waveforms.

The circuit arrangement for the signal translator provides for the initial clearing, i.e., saturating the translator core 12, by coupling a clearing signal 54 to the clearing circuit input terminal 56. The clearing signal is coupled to the clearing winding 34 having an opposite end connected to a ground 58. A clearing signal having the proper polarity as indicated in FIG. 1 initially saturates the translator core in the clockwise direction.

A setting signal 60 is coupled to the input terminal 62 of the circuit 16 to store magnetic flux in the translator core by applying a demagnetizing force to the core to place the core in a partial state of saturation, preferably at a residual state between points 1 and 4 on the vertical axis of the ϕ -H curve, illustrated in FIG. 4a. The setting signal is coupled from the input terminal 62 to the base of the transistor 64 by a parallel input circuit 66 including a source of positive bias 68. Preferably the transistor 64 is of the PNP type having an emitter coupled to ground and a collector connected to one end of the setting winding 46. The opposite end of the setting winding is connected to the setting winding supply voltage which is clamped to a predetermined voltage, e.g., -4 volts. The supply circuit providing the clamped voltage includes a diode 70 connecting a clamped voltage supply source, e.g., -4 volts, to the setting winding and a higher voltage supply source, e.g., -50 volts, through a current limiting resistor 72.

Signal delay circuit 18 includes an input circuit having an input terminal 74 and a parallel input coupling circuit 76 for coupling an input signal waveform 78 to the base of a transistor 80, which is preferably of the PNP type. A collector of the transistor 80 couples the input signal waveform to the delay circuit winding whereby the initial variations in the signal waveform are delayed during the reversal of the stored magnetic flux around the minor aperture 30. The signal delay winding 48 is threaded through the minor aperture 30 and wound around the outer core portion 38. The opposite end of the signal delay winding is coupled to voltage supply sources which are common to both the signal delay circuit and the resetting circuit. The voltage supplied to the signal delay circuit is clamped at 4v by a supply circuit including a diode 81.

The collector of a transistor 86 is coupled to the output of the signal delay circuit and the output terminal 88. The transistor 86, preferably of the PNP type, has an emitter coupled to a ground 94 whereby the output circuit is connected to ground through an alternate path during the time period the stored magnetic flux is being reset. Thus, in response to the negative portion 90 of resetting signal V_R , the output circuit is coupled to ground through this alternate path including the transistor 86.

There may be a very brief time interval between the trailing edge of the input signal and the leading edge of the negative portion 90 of the resetting signal. In order to maintain a connection to ground via transistor 86 during this brief time interval, the base of the transistor 86 is coupled to a lead connecting the collector of the transistor 80 to the signal delay winding 48 by a capacitor 92. The capacitor 92 has a short response time and develops a negative charge that is coupled to the base of the transistor 86 whereby it is made conductive to couple the output of signal delay circuit to the ground 94. As a result of this coupling, the output signal will not follow the trailing edge of the input signal during the brief interval between the trailing edge of the input signal and the leading edge of the negative portion 90 of the resetting signal. The transistor 86 remains conductive until the negative portion 90 of the resetting signal takes over to maintain conduction through transistor 86 and therefore maintain connection of the output circuit to ground through the alternate path.

In the operation of the preferred embodiment, shown in FIG. 1, a clearing signal 54 is coupled to the translator core 12 by a clearing winding 34 to saturate the core about the major aperture 32 in a clockwise direction in major flux paths indicated by the arrows 26, 27, and 28. After the translator core is saturated by the clearing signal 54, a setting signal is coupled to the core by a setting signal winding 46. The setting signal 60 provides a predetermined volt-microsecond signal corresponding to the desired time period of delay. The setting signal winding applies to demagnetizing force to the core to reverse the flow of magnetic flux in the major flux paths, preferably setting the core in a residual state of magnetism between states 1 and 4, as indicated by the curve in FIG. 4a. The reversal of magnetic flux flow in the major flux paths, as indicated by the arrows 42 and 44 in FIG. 3, also reverses the flux in the inner core portion 40 between the apertures 30 and 32. The reversal of magnetic flux in the inner core portion 40 produces magnetic flux flow in annular minor flux paths around the minor aperture 30. The flow of magnetic flux about the minor aperture 30 can now be considered separately and individually until it is necessary to store a different magnitude of magnetic flux about the minor aperture to provide different time periods of delay. The magnetic flux which is available for reversal about the minor aperture 30 by windings 48 and 50 or other interrogation windings, which are threaded through the minor aperture 30 only, or other minor apertures in a more than two-apertured core, is the stored magnetic flux in the translator core. The reversal of the stored magnetic flux in the minor flux paths will produce a curve similar to one of the typical hysteresis curves 1a to 7a, shown in the family of curves in FIG. 4b.

Referring now to the delay portion of the circuit for a description of its operation, the signal waveform 78 to be delayed is applied at the input terminals 74. The variations in level of the signal waveform, i.e., the leading and trailing edges are separated by time intervals which are at least equal to and preferably greater than the time period of delay to prevent loss of a portion of the signals. When the signal waveform goes negative at its leading edge, the transistor 80 conducts and

the clamped voltage supply (-4 v.) is coupled directly across the winding 48. The current through the signal delay winding 48 is delayed during the time interval the stored magnetic flux in the minor flux paths 24 around the aperture 30 is being reversed. After reversal of the stored magnetic flux, the resistor 96 acts as a current limiter and the signal output voltage rises to ground potential from the level (-4 v.) of the clamped supply voltage. Thus, as shown in FIG. 2, the leading edge of the signal waveform V_0 is delayed for the particular time period of the delay set into the translator circuit.

While the input signal is still negative the current in the signal delay winding 48 provides a sufficient number of ampere-turns on the core portion 38 to overcome the ampere-turns produced by the resetting winding 50. In the preferred arrangement, the ampere-turns of the signal winding 48, during the time interval of the input signal, is approximately twice the ampere-turns produced by the resetting winding 50 under quiescent conditions. During the time interval of the input signal, the resultant ampere turns produced by the signal delay winding prevents the resetting of the stored magnetic flux and the stored magnetic flux in the core portion around the minor aperture remains reversed.

When the input signal level returns, at the trailing edge 98, the transistor 80 will turn off and a negative spike is produced in the winding 48. The negative spike is coupled by the capacitor 92 to the base of the transistor 86 to turn on the transistor 86 to provide an alternate path to ground for the supply current in the output of the signal delay circuit.

In order to delay the trailing edge or return of the output signal for the entire time period of delay, the resetting circuit takes over control of the translator. At the trailing edge of the input signal waveform, after the transistor 80 has gone into a state of non-conduction, the resetting circuit, including the winding 50, produces a magnetizing force in the outer core portion about aperture 30 to reset the stored magnetic flux in the minor flux paths about the minor aperture 30. During the time interval the stored magnetic flux is being reset, the end of the resetting winding connected to the voltage supply goes negative by an amount determined by the clamped supply voltage. The time interval required for resetting the stored magnetic flux around the minor aperture is equal to the time period the input signal was delayed in the signal delay output circuit, i.e., during the period of reversal of stored magnetic flux. After the stored magnetic flux around the minor aperture is reset, the resetting signal returns to the bias signal level of the quiescent state and the transistor 86 is returned to its non-conductive state. Upon the transistor 86 returning to its non-conductive state, the output of the signal delay circuit is disconnected from ground through the alternate path and the output signal is returned to the signal level of its clamped supply voltage (-4 v.). The time interval of the input and output signals of the delay circuit are substantially equal and the input signal has been delayed for the desired time period.

Referring now to FIG. 5, an alternate embodiment has been shown in which a signal translator circuit 100 includes a conventional toroidal core 102 formed from magnetic material having a hysteresis characteristic which is approximately rectangular. The toroid forming the translator core 102 is magnetically coupled to each of several operational circuits by their respective windings. A clearing circuit 104 includes a winding 106 threaded through an aperture 103 and wound around the core. One end of the clearing winding is coupled to the clearing circuit input terminal 110 which is provided for coupling the clearing signals V_c to the clearing winding and to ground 114. In the preferred arrangement of the alternative embodiment shown in FIG. 5, the clearing circuit

saturates core 102 with magnetic flux flowing in the clockwise direction as indicated by the arrow 112.

In FIG. 7, a typical hysteresis characteristic curve of a core suitable for use in the circuit of FIG. 5 has been illustrated. In a typical clearing operation the clearing signal initially drives the core 102 into a state of saturation, indicated generally by the reference character 116 in FIG. 7, in response to an applied magnetizing force H . After the clearing pulse, the core returns to a residual state of flux at point 118 in FIG. 7.

A setting circuit 121 is coupled to the translator core 102 by a winding 122 threaded through the aperture 103 and wound around a portion of the core. The circuit arrangement for storing magnetic flux in the core 102 is similar to the circuit provided in FIG. 1 for storing magnetic flux in the core 12. A setting signal having a predetermined time interval is coupled to an input terminal 126 connected to the base of the transistor 128. The transistor 128 controls the current from a supply source through the setting winding 122 wherein the total magnetic flux stored in the core is dependent upon the time interval of the setting signal and the supply voltage for the setting circuit. The supply voltage for the setting winding 122 is clamped at a predetermined voltage, e.g., -4 volts, by a supply circuit 129.

The collector of the transistor 128 is coupled to the output of a signal delay circuit 130. In the preferred arrangement of the circuit shown in FIG. 5, the leading edge of the setting signal 124 is timed to occur simultaneously with the trailing edge of the input signal. As shown in FIG. 6, the trailing edges or returns in level of the input signal in the output circuit are delayed by the addition of the inverted setting signal pulse V_R to the output signal V_0 . The signal V_R is coupled to the output of the signal delay circuit by a diode 132 and a lead 135 connected to the collector of the transistor 128.

The signal delay circuit 130 includes a signal delay winding 134 which is threaded through the aperture 103 wound around a portion of the core 102. The signal to be delayed is coupled to the delay winding by an input circuit including an input terminal 136 and a parallel network 138 coupled to a bias supply source at the terminal 140. The input circuit couples the signals to the base of the transistor 142 having an emitter connected to ground and a collector coupled to an end of the delay winding. The opposite end of the delay winding is coupled to a winding supply voltage which is clamped to a predetermined voltage, e.g., -4 volts, by a supply circuit including a diode 144 and a current limiting resistor 146. The output circuit includes a diode 148 which couples delayed output signals from the delay winding to an output terminal 150. The diodes 132 and 148 are coupled to a negative voltage supply terminal 152 through a summing resistor 154 whereby portions of the output signal coupled to either diode are formed on output terminal 150. For example, the delayed signal level above the clamped voltage of the supply, corresponding to the leading edge of the output signal V_0 , is passed through diode 132; and a signal level above the clamped voltage of the supply, as passed through diode 148, effectively serves to delay the return of the output signal V_0 during the time interval of the signal V_R . The signal V_R has a time interval which is equal to the time interval of the setting signal 124.

In operation, the translator core 102 is driven into saturation by a clearing signal V_c applying a magnetizing force to the core by the clearing winding 106 to saturate the core with magnetic flux flow in the clockwise direction as indicated by the arrow 112. Subsequently, a setting signal applies a demagnetizing force to the core to reverse the magnetic flux in the inner radial portion of the core, driving the core into a state of partial saturation, i.e., a residual state of magnetism, e.g., at a point ϕ_R on the vertical axis where the portion 160 of the curve, indicated by the dotted line, intersects the vertical axis. The available magnetic flux stored in the core is equal

to the difference in flux of the residual states of magnetism, e.g., the difference in flux of residual states indicated in FIG. 7 at 118 and ϕ_R .

The signals to be delayed, V_{IN} , are sequentially coupled to the transistor 142 to apply magnetizing forces to the core 102 by the delay winding 134. The magnetizing force produced by each signal drives the core back into saturation, indicated on the curve of FIG. 7 at 116. During the interval the core 102 is being driven back into saturation, the leading edges of signals are delayed, preferably for the same time period which was required for setting the core. During the remaining time interval of the input signal, the transistor 142 remains conductive and the signal output level remains constant.

The output signal level of the signal delay circuit is prevented from returning at the trailing edge of the input signal and the trailing edge is delayed in the output by the signal V_R whose leading edge is coincident with the trailing edge of the input signal V_{IN} . As shown, the trailing edge of the output signal is delayed by the same time period that the leading edge was delayed, assuming that the number of windings in 134 and 122 are equal, whereby the time interval between leading and trailing edges of the input and output signals remains substantially constant.

As can be seen from the discussion of the operation of the circuit FIG. 5, an input signal can be delayed for a time period which can be varied by a setting signal where the period of delay varies between 0 and the time interval of the signal to be delayed.

In light of the above teachings, various modifications of the invention are contemplated and will be apparent to those skilled in the art without departing from the spirit and scope of the invention. For example, a translator core can be set by a permanent magnet or other means capable of applying predetermined magnetizing force to the core to set the core by storing any desired magnetic flux therein. Also, the clearing circuit arrangement for clearing the translator core can be modified or eliminated by providing other means for saturating the core by applying a magnetizing force to the core to produce magnetic flux saturating the core in a predetermined direction. Saturation of the core can be followed by a setting or storing in which a demagnetizing force is applied to the core by suitable means to reverse the flow of magnetic flux in the core. Also, in the preferred embodiment of FIG. 1, or the alternate embodiment of FIG. 5, the size of the core may be tailored to the desired time period of delay in which the magnetic flux stored therein at saturation corresponds to the desired time period of delay of the signals coupled to the core. Also, by adjusting circuit parameters, i.e., ampere-turns of the windings, the time period of delay may be adjusted relative to the magnetic flux stored in a translator core, for example, the turns of the windings and the clamped voltage may be adjusted in the signal delay circuit to vary the period of delay for a given stored magnetic flux in the core.

What is claimed is:

1. In combination, with a core having major concentric flux paths about a major aperture and minor concentric flux paths about a minor aperture wherein the minor flux paths provide for the storage of predetermined different magnitudes of residual magnetic flux, a circuit arrangement for delaying variations in level of pulses to be delayed comprising: means coupled to the core for storing predetermined different magnitudes of residual magnetic flux in the minor flux paths wherein the magnitude of the magnetic flux is a function of the desired delay; and circuit means having an input and output and a pulse delay winding having one end thereof coupled to said input and the other end coupled to said output for serially interconnecting the input to the output, said winding being threaded through said minor aperture for coupling said pulses to be delayed to the core to reverse the direction of the magnetic flux stored in the minor

flux paths to reduce the impedance of said winding to place both ends of said winding at substantially the same level after said magnetic flux reversal, said circuit means being operative in response to each of the pulses applied on the input to produce a delayed pulse in the output wherein the time period of delay is substantially equal to the time interval required to reverse the stored magnetic flux in the minor magnetic flux paths.

2. A translator circuit arrangement for providing an adjustable delay period which comprises: a translator core of magnetic material having a hysteresis characteristic which is approximately rectangular, said core having a plurality of apertures including a major aperture and a minor aperture; a clearing winding threading the major aperture to induce a magnetizing force and a magnetic flux around the major aperture for saturating the core in a first direction; circuit means including a setting winding threading at least the major aperture for coupling a constant amplitude signal having a predetermined time period which is a function of the preselected period of delay wherein said latter signal produces a demagnetizing force in the core and a predetermined stored magnetic flux about the minor aperture; signal circuit means including a signal delay winding threading a minor aperture, a signal output coupled to one end of said signal delay winding and an input coupling signals to be delayed to the other end of said signal delay winding, each of said signals coupled to said input producing a magnetizing force reversing the direction of stored magnetic flux around said minor aperture to produce respective signals at said signal output which are delayed for said preselected period; resetting circuit means coupled to said signal output including a resetting winding for producing a magnetizing force around said minor aperture for resetting the stored magnetic flux around the minor aperture in the absence of a signal on the signal delay winding, said resetting circuit means being responsive to the reversal of magnetic flux flow during resetting of the stored magnetic flux to produce a reset signal having a time duration that is a function of the magnitude of the stored magnetic flux and that is substantially the same as the time period of delay of the signals, whereby each of the signals in the output of said signal circuit means is delayed for the desired time period and is of the same time duration.

3. A translator circuit arrangement for providing an adjustable delay period which comprises: a translator core of magnetic material having a hysteresis characteristic which is approximately rectangular, said core having a plurality of apertures including a major aperture and a minor aperture; a clearing winding threading said major aperture to induce a magnetizing force and a magnetic flux around the major aperture for saturating the core in a first direction; setting circuit means including a setting winding threaded through at least the major aperture for coupling a constant amplitude signal having a predetermined voltage time period which is a function of the preselected period of delay wherein said latter signal produces a demagnetizing force in the core inducing a predetermined stored magnetic flux in the opposite direction around the minor aperture and magnetic flux flow in minor flux paths around said minor aperture; signal circuit means including a signal delay winding threaded through said minor aperture and wound about the outer minor core portion, a signal output coupled to one end of said signal delay winding and an input coupling signals to be delayed to the other end of said signal delay winding, each of said signals coupled to said input producing a magnetizing force around said minor aperture for reversing the direction of stored magnetic flux in said minor flux paths to produce respective signals at said signal output which are delayed for said preselected period; and resetting circuit means coupled to said signal output including a resetting winding for producing a magnetizing

11

force for resetting the stored magnetic flux around the minor aperture at the termination of the signal on the signal delay winding, said resetting circuit means being responsive to the reversal of magnetic flux flow during resetting of the stored magnetic flux to produce a reset signal having a time duration which is a function of the magnitude of the stored magnetic flux and is substantially the same time period as the time period of delay of the signals, whereby each of the signals in the output is delayed for the desired time period and reformed in the output.

4. In combination with a translator core of magnetic material having at least one major aperture and at least one minor aperture providing annular major and minor flux paths for storing preselected magnitudes of magnetic flux, a circuit arrangement for delaying input pulses and producing a delayed output pulse having the same time duration as each respective input pulse comprising: setting circuit means coupled to the translator core for coupling a setting signal having a constant voltage and a predetermined time interval which is a function of the desired time period of delay to apply a demagnetizing force in the translator core for storing a predetermined magnetic flux; signal circuit means having an input and an output coupled to the core for producing a magnetizing force in the core in response to each of the input pulses coupled to the input to reverse the direction of flux flow of all of the stored magnetic flux in the annular minor flux paths whereby the leading edges of each of the input pulses are delayed in said output during the respective flux reversals; and resetting circuit means coupled to the core to produce a magnetizing force for resetting the direction of flow of the stored magnetic flux after each input pulse and between each of the input pulses, said reset circuit means also being coupled to the output of said signal circuit means and producing a reset signal after each input pulse during the time interval the stored magnetic flux in the minor flux paths is being reset to delay the trailing edges of each of the input pulses in the output for the same time period as the leading edges of the pulses.

5. A translator circuit for delaying a signal waveform which is characterized by a change from a first potential level to a second potential level and back to the first potential level and producing an output signal waveform having the same time duration as each respective input signal waveform, comprising: a core of magnetic material; means for storing magnetic flux in the core wherein the magnitude of the flux is a function of the desired time period of delay to be given to said signal waveform; circuit means for applying said signal waveform to said core to reverse the magnetic flux stored therein to delay the appearance on the output of said circuit means of the change of said signal waveform from said first potential level to said second potential level during the time period of the reversal of said stored magnetic flux; and means restoring said magnetic flux into the core and delaying the appearance on the output of said circuit means of the change of said signal waveform from said second potential level back to said first potential level.

6. A translator circuit for delaying a rectangularly shaped signal waveform to provide an output signal waveform having the same time duration as each respective input signal waveform comprising: a core of magnetic material; adjustable means for storing magnetic flux in the core wherein the magnitude of the flux is a function of the desired time period of delay to be given to said signal waveform; circuit means having an input and an output connected by a winding inductively coupled to said core; means for applying said signal waveform to the input of said circuit means to reverse the magnetic flux stored in said core to thereby delay the appearance of the leading edge of the signal waveform on the output of said circuit means during the time period

12

of reversal of said stored magnetic flux; a resetting circuit means having a winding coupled to said core and responsive to the termination of said signal waveform to restore the magnetic flux in the core in a time period equal to the time period of reversal of said stored magnetic flux; and switching means coupling said resetting circuit means to the output of said circuit means for extending the duration of the signal waveform on the output of said circuit means for the time interval that the magnetic flux is being restored back into the core.

7. A delay circuit producing an output signal waveform having the same time duration as each respective input signal waveform comprising: a magnetic core; a setting winding inductively coupling a setting signal source to the core and operative when energized to coerce at least a portion of the core to a selected first state of flux; a signal delay winding coupling an input signal source to at least a portion of the core and operative in response to the leading portion of an input signal waveform supplied thereto to coerce the said at least a portion of the core to a second flux state, to thereby delay the appearance of the leading edge of the output signal waveform on the output of said delay winding during the time period of said change in state of flux; means including a restore winding coupling a direct current bias source to the core capable of coercing said at least a portion of the core back into said first state in the absence of any input signal waveform to restore the said at least a portion of the core to the said first flux state following the cessation of said input signal waveform on said signal delay winding; and circuit means coupling said signal delay winding and said restore winding for extending the duration of the said output signal waveform for a time interval equal to the delay of the leading edge of the output signal by connecting said bias source to the output of said delay winding during the restoration of said at least a portion of the core to the said first flux state.

8. A delay circuit for providing a delayed output signal waveform having the same time duration as each respective input signal waveform comprising: a saturable magnetic core; a first means coupled to the core for coercing at least a portion of the core to a selected first flux state; a signal delay winding coupled to the core; switching means for supplying to the signal delay winding an input signal waveform of a predetermined amplitude, the leading portion of which is dissipated in coercing the core to a second flux state such that in dependence upon the particular first flux state selected, the leading edge of the output signal waveform is delayed, by a predetermined time interval during the change in flux states, relative to the leading edge of the input signal waveform; means including a restore winding coupled to the core and effective following cessation of the input signal waveform to restore the said at least a portion of the core to the first flux state in said predetermined time interval; and an alternate current source means including a switching means coupling the output of the signal delay winding and the restore winding such that in response to the potential present on the restore winding during restoration of at least a portion of a core, the duration of the output signal waveform is effectively extended for a time interval equal to the dissipated leading portion of the input signal waveform.

9. A delay circuit providing an output pulse for each input pulse comprising: a multi-aperture magnetic core formed of a magnetic material having a high residual magnetism and a hysteresis characteristic curve which is substantially rectangular, said core having a major aperture in the center and a minor aperture which is offset from the center of the core; circuit means for saturating said core in a first direction around said major aperture and producing a magnetic flux in the opposite direction for storing a residual magnetic flux in concentric magnetic flux paths around said minor aperture,

said circuit means including a set winding threading said major aperture and set switching means coupled to said set winding for coupling a set pulse having a variable time duration and a predetermined voltage amplitude to said set winding; signal delay circuit means for reversing the residual magnetic flux stored around said minor aperture in a time period equal to the time duration of the set pulse storing said residual magnetic flux, in response to said input pulse, said delay circuit means including an input, an output, signal switching means coupled to said input, a signal delay winding threading said minor aperture and coupling the output of said switching means to said signal delay circuit output, said switching means being responsive to said input pulse to produce a pulse of said predetermined voltage amplitude on said signal delay winding; reset circuit means including a reset winding threading said minor aperture; and pulse forming switching means having an input coupled to the output of said signal delay circuit switching means and to said reset winding, and a pulse forming circuit output coupled to the output of said delay circuit means, said reset winding being connected to a source of bias potential capable of restoring said residual flux about said minor aperture during the time interval of delay in the absence of an input pulse of said predetermined amplitude on said delay winding, said pulse forming switching means being connected to a source of said predetermined voltage amplitude and responsive to a reset pulse produced on the reset winding during restoration of said residual magnetic flux to produce a pulse on the delay circuit output for maintaining the output signal level during the time period of restoration of said residual magnetic flux whereby the output pulses produced by said delay circuit are of the same time duration as the time duration of the input pulses and delayed for the time period of said set pulse.

10. The method of delaying pulses to provide a delayed output pulse for each input pulse which comprises: magnetically storing a setting signal by producing a magnetizing force in a core of magnetic material and storing a magnetic flux the magnitude of which is a predetermined function of a desired time period of delay; producing a magnetizing force by each input pulse to be delayed to reverse all of the magnetic flux in the core produced by the stored setting signal in a time interval which is substantially equal to the time period of delay, whereby the leading edge of each input pulse is delayed for said time period; producing a magnetizing force which is initiated at the trailing edge of each input pulse for resetting the stored magnetic flux back into the core; and delaying the trailing edge of each input pulse in the output during the time interval that the stored magnetic flux is being reset.

11. The method of delaying pulses wherein a delayed output pulse is produced for each input pulse which method comprises: magnetically storing a residual flux in at least a portion of a core by a set pulse of adjustable time duration and producing a predetermined magnetizing force wherein the magnitude of the magnetic flux is a predetermined function of a desired time period of delay; coupling an input pulse to be delayed to said core and to an output to produce the same predetermined magnetizing force for reversing said residual flux to saturate said portion of said core wherein the leading edge of said pulse

- is delayed in said output for the same time period as the set pulse; producing a reset pulse beginning at the trailing edge of the input pulse having a time duration equal to said time period of delay; and coupling said reset pulse to said output to delay the trailing edge of the pulse in the output to reform the input pulse and to said core to restore the residual flux in said core for delaying the next input pulse to be delayed and for the same time period.
- 10 12. The method of delaying signals having a longer time duration than the period of delay in which an output signal is produced for each input signal comprising: storing a residual magnetic flux about an aperture in a core of magnetic material in a first direction wherein the magnitude of the residual magnetic flux is adjustably controlled to produce the desired time delay of said signal; inductively coupling a first portion of an input signal to said core to produce an input magnetizing force for reversing the residual flux stored therein and coupling the remaining portion of said input signal to an output to thereby provide the first portion of an output signal having a delayed leading edge equal to said time delay; continuously applying a resetting magnetizing force to said core which force is less than said input magnetizing force to said core to restore said residual magnetic flux in a time period equal to the time period of delay; producing a signal in said output in response to said restoration of said residual flux beginning at the trailing edge of said input signal to maintain the signal level of said output signal and delay the trailing edge of the output signal for the desired time delay, whereby the output signal has the same time duration as the input signal but delayed for the desired time period and said residual magnetic flux is restored in the core for delaying the next input signal for the desired time period of delay.

13. The method of delaying pulses wherein a delayed output pulse is produced for each input pulse which method comprises: magnetically storing a residual flux in at least a portion of a core wherein the magnitude of the magnetic flux is a predetermined function of a desired time period of delay; coupling an input pulse to be delayed to said portion of said core and to an output to produce a magnetizing force in said portion of said core for reversing said residual flux to saturate said portion of said core wherein the formation of the leading edge of said pulse is delayed in said output during the time period of residual flux reversal; applying an opposing magnetizing force to said portion of said core capable of restoring said residual magnetic flux in said portion in the desired time period of delay in the absence of an input pulse; producing a pulse having a time duration equal to said time period of delay in response to the change in flux during the restoring of the residual magnetic flux in said portion of said core; and coupling said pulse to said output to delay the formation of the trailing edge of said input pulse whereby the delayed pulse in the output has the same time duration as the input pulse.
